CLAIM

The ornamental design for a box, as shown and described.

DESCRIPTION

FIG. 1 is a front, left and top perspective view of a box, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is another front, left and top perspective view of the box of FIG. 1 in an open state.

FIG. 10 is an enlarged view of detail 10 in FIG. 1.

FIG. 11 is an enlarged view of detail 11 in FIG. 1.

FIG. 12 is an enlarged view of detail 12 in FIG. 1; and,

FIG. 13 is an enlarged view of detail 13 in FIG. 1.

The evenly broken lines depict portions of the box that form no part of the claimed design. The dot-dash broken lines in FIGS. 1 and 10-13 represent the designation of enlargement views and form no part of the claimed design.

1 Claim, 13 Drawing Sheets
